UNITED STATES PATENT OFFICE

135,344

DESIGN FOR A BACKSTAND FOR BELT POLISHING MACHINES

Edward C. Krueger, Otsego, Mich., assignor to
Hammond Machinery Builders, Inc., Kalama-
zoo, Mich., a corporation of Michigan

Application January 11, 1943, Serial No. 109,231

Term of patent 14 years

To all whom it may concern:

Be it known that I, Edward C. Krueger, a citizen of the United States, residing at Otsego, in the county of Allegan and State of Michigan, have invented a new, original, and ornamental Design for a Backstand for Belt Polishing Machines, of which the following is a specification, reference being had to the accompanying drawing, forming part thereof, in which

Fig. 1 is a side elevational,

Fig. 2 is a rear elevational, and

Fig. 3 is a front elevational view on a reduced scale of a backstand for belt polishing machines, showing my new design.

I claim:

The ornamental design for a backstand for belt polishing machines, substantially as shown.

EDWARD C. KRUEGER.
